UNITED STATES PATENT OFFICE.

SAMUEL J. WATSON, OF CHICAGO, ILLINOIS, ASSIGNOR TO LAMBETH S. ALLEN, OF CHICAGO, ILLINOIS.

LETTER-SHEET.

1,000,466.

Specification of Letters Patent. Patented Aug. 15, 1911.

Application filed May 21, 1908. Serial No. 434,105

To all whom it may concern:

Be it known that I, SAMUEL J. WATSON, a citizen of the United States, residing at Chicago, Illinois, have invented certain new 5 and useful Improvements in Letter-Sheets, of which the following is a specification.

This invention has reference primarily to letter sheets in which the sendee's name and address as it occurs on the letter serves also 10 as the address of the letter when folded, eliminating the need of any separate envelop or the addition of any separate writing of the sendee's name upon the outside of the sheet after it is folded.

15 One of the primary objects of this invention is the provision of a letter sheet of this character which will be easily folded, and which will not require more paper than the usual size of letter sheets, and in which the 20 arrangement of the matter upon the sheet and of the sendee's name as well as the signature, and of the folds employed in folding the sheet, will be substantially the same as is ordinarily used, and not require special 25 facility or any special arrangement with a diagram of instructions indicating how the sheet should be folded.

The above, as well as such other objects as may hereinafter appear, I attain by 30 means of the construction which I have illustrated in the accompanying drawings, wherein—

Figure 1 indicates a letter sheet made in accordance with my improvement, with the 35 part which it is intended to fold back to expose the sendee's name, shown in the position which it occupies at first; Fig. 2 shows the letter sheet with the exposure flap folded preparatory to the folding of the sheet; Fig. 40 3 shows the sheet entirely folded, with the sendee's name and address disclosed through the exposure opening or window, and Fig. 4 is a sectional view on the line IV—IV of Fig. 3, showing the relation of the several 45 parts.

In carrying out my improvement I first

provide a sheet similar to that shown in Figs. 1 and 2, which has a place indicated at 5, for the location of the sendee's name and address which occur in the customary 50 form, and below which, as indicated at 6, is the main or body portion of the letter or circular. Within the body portion of the letter, as indicated by the line 7, I arrange a slit forming a flap 8 which when folded 55 back upon the line 9 will expose the sendee's name when the upper part of the letter sheet 10 is folded downward along the line 11. The position of the flap 8 before the part 10 is folded on the line 11, is indicated in Fig. 2 60 in which as will clearly appear there is an opening 8a which comes in exactly the right location to expose the sendee's name (which is almost immediately above said opening), as indicated in Fig. 3, when the sheet is 65 entirely folded, the portion of the sheet marked 12 being the last to be folded over. In order to secure the sheet I can use a paster similar to that indicated at 13, or any other convenient means for holding the 70 parts together.

Having thus described my invention and illustrated its use, what I claim as new and desire to secure by Letters Patent, is the following:

75 / A letter sheet having a transverse line of folding dividing the sheet into upper and lower portions, the portions being provided respectively with a space for the sendee's name and address and an exposure opening 80 in opposition longitudinally of the sheet and at substantially equal distances from the line of folding, and a flap for closing the opening adapted when closed to receive a portion of the matter imprinted on the sheet. 85

In testimony whereof I have hereunto signed my name in the presence of the two subscribing witnesses.

SAMUEL J. WATSON.
